DOOR CONSTRUCTION

Robert A. Miller, Tarentum, Pa., assignor to
 Pittsburgh Plate Glass Company, Allegheny
 County, Pa., a corporation of Pennsylvania

Application May 11, 1938, Serial No. 207,272

5 Claims. (Cl. 20—16)

The present invention relates to closures and it has particular relation to closures of the swinging type and of relatively large dimensions suitable for use as doors in passageways of buildings.

The main object of the invention is to provide a large, swinging closure suitable for use as a door in a building and comprising a single panel of glass, which panel is self-sustaining upon its hinges.

A further object of the invention is to provide a novel method of securing the hinges to a door of the foregoing type.

These and other objects of the invention will be apparent from consideration of the following specification and the appended claims.

Doors for dwellings have heretofore been constructed of wood, sheet steel or similar material. In some cases panels of glass were inserted in the doors to provide for the transmission of light through the door or to obtain ornamental effects. In such doors, the glass merely closed an opening in the swinging member and was supported and reinforced by the latter, and little or no localized stress from the hinges was placed upon it.

Apparently, unitary doors comprising an unsupported panel of glass which acted as the movable barrier element and which also transmitted its own weight as well as other stresses to the hinges was not contemplated. Probably such doors constructed of the same quality of glass as the glass insert panels would have been too fragile to be practicable.

The present invention contemplates the provision of a door comprising a single panel of relatively strong, resilient tempered glass to which the hinge elements are directly attached. As an additional feature, the invention contemplates the provision of a satisfactory method of securing the hinges to the panel.

Tempered glass suitable for forming the doors constituting the subject matter of the present invention is obtained by heating ordinary sheet glass to a temperature of 1100 or 1200 degrees F. and then suddenly cooling it by plunging it into oil or by the direct application of a blast of cold air. Glass so treated assumes a mechanical strength almost equal to cast iron and is quite springy, or resilient. It is also quite capable of withstanding severe impacts or blows and severe mechanical stresses. If for any reason the door is broken, the glass instantly shatters into small rounded fragments which are quite harmless if they should strike a person adjacent to, or passing through, the doorway.

For a better understanding of the invention, reference may now be had to the accompanying drawings in which

Figure 1 is a fragmentary cross-sectional view showing a portion of a door panel together with certain features of the hinge structure.

Figure 2 is a fragmentary view taken in a plane at right angles to the plane of Figure 1.

Figure 3 is a cross-sectional view taken horizontally through a door of revolving type embodying one form of the invention.

Figure 4 is a cross-sectional view taken substantially upon the line IV—IV of Fig. 3.

Figure 5 is a cross-sectional view taken substantially upon the line V—V of Fig. 3.

Figure 6 is a detail view of a cross member employed to hold the panels comprising the door in assembled relation.

Figure 7 is a detailed cross-sectional view of a wiper construction for sealing about the edges of the door panels.

Figure 8 is an elevational view of a pair of doors embodying the invention.

Figure 9 is a sectional view corresponding to Figure 1 but showing a slightly modified form of the invention.

Figure 10 is a fragmentary elevational view corresponding to Figure 2 but showing the modified form of the invention illustrated by Figure 9.

In the form of the invention illustrated in the drawings, a building wall 11, composed of masonry or any other suitable building material is provided with an opening in which are disposed the doors 12. These doors preferably consist of single panels of glass, tempered to a strength approximately four times that of untempered glass. The panel may be of substantially any preferred thickness. However, a range of about $\frac{1}{2}$ to 1 or $1\frac{1}{4}$ inches is preferred. A satisfactory thickness for most purposes is about $\frac{3}{4}$ inch.

Various forms and types of hinges may be employed in mounting the doors, but in view of the peculiar characteristics of the tempered glass panel in most instances it is necessary to provide specialized forms of securing devices for connecting the hinge to the panel. The drawings illustrate a satisfactory form of hinge and the method of securing it to the panel. These hinges include pins projecting from the top and bottom edges of the door panel and rotating in suitable bearings in the floor and the lintel of the door. The top hinge structure 15, includes a pair of side plates 16, gripping opposite sides of the glass panel and a casting 17, of a thickness corresponding to the thickness of the glass

panel and providing a spacing element between the plate 16. This casting is secured in a notch 19, formed at the upper corner of the glass panel and having a rounded corner 20. Plates 16 and casting 17 may be secured together by welding or by bolts. The mechanical pressure of the plates upon the sides of the glass panel may be relied upon to hold the parts in position upon the latter. However, the means for securing the panel illustrated in the drawings comprises a bolt 21, threaded through a sleeve 22, both of which have heads 23. The bolt and sleeve are secured in openings in the plate 16 whereby upon tightening of the bolt, the plates will be caused to grip the glass. The edge of the notch 19 is provided with a semi-circular recess 24 to receive bolt 21 and sleeve 22, and the space between the sleeve and recess is filled with a suitable resilient packing such as fibre or the like.

It is important to note that the corner 20 of the recess 19 and notch 24 are rounded to a curvature having a radius at least equal to half the thickness of the panel. Any holes in the glass must have radii at least equal to half the thickness of the glass panel. It is found to be impossible to provide a glass panel of tempered glass possessing satisfactory stability, if radii of lesser value are employed. Semi-circular recesses 24 may be replaced by holes formed in the panels at some distance from the edge. Casting 17 is hollowed as indicated at 26 to receive a plate 27 which may be secured in position by welding, riveting or bolting to the side of the casting or in any other convenient manner and the plate at each end is provided with a downwardly-extending boss 28 which extends into a well 29 formed in the casting 27.

This boss is bored as indicated at 30 to receive a hinge pin 31 that extends upwardly through a boss 32 upon a fixed plate 33 secured by bolts 34 to a lintel 35. The lintel is slotted as indicated at 37, to receive a pair of lugs 38 through which extend a pin 39, constituting a pivot for a lever 41, the forward extremity of which extends through a slot 42 formed in the side of boss 32 into a recess 43 in pin 31. The lever at its opposite end is formed with a slot (not shown) to receive a grooved portion 46 of a pin 47 which is threaded through the plate 33. At its lower end, the pin is formed with a slot 48 within which the end of a screw driver may be inserted for rotating the pin to actuate the lever up or down to raise or lower the pin 31.

At the corresponding lower corner the panel is notched as indicated at 50 to receive a casting 51 substantially corresponding to the casting 17 already described. The lever or arm 52 is mounted in hollow 53 in this casting and is secured to the side walls of the hollow by welding or by other convenient methods. A square recess 54 is formed in the lever adjacent to its rear end receives the square stem 55 of a vertically disposed hinge pin or shaft 56. At its lower extremity it is connected to a suitable actuating means for rotating the shaft to swing the door back to closed position after it has been opened. Such mechanism also includes suitable dashpot mechanism for checking the rate of swing. These various mechanisms are concealed beneath the floor or sill 57 and since they do not constitute a portion of the present invention it is not deemed necessary to describe them in detail. Casting 51 is clamped in position by means of side plates 60 corresponding to plates 16 and held in place by a sleeve bolt 61 identical in de-

sign and mounting to that described in connection with the upper hinge.

If desired, the side plates 16 may be recessed as indicated at 62 to provide additional space for shaft 55.

It will be apparent to those skilled in the art that top hinge pin 31 and shaft 55 need not be disposed directly in the plane of the door panel. It is, of course, possible to provide laterally or rearwardly-extending arms upon the casting 17 and casting 51 and to secure suitable hinge pins in these openings. The method securing such hinges, of course, would substantially correspond to that shown in the drawings. It would involve the provision of notches at the corners of the doors or at other suitable locations along the rear edge of the doors adapted to receive a spacing body corresponding to the casting 17 or casting 51 of sufficient rigidity to support the hinge pin and being provided with suitable side plates corresponding to the plates 16 and 60.

The structures shown in Figures 3 to 7 inclusive illustrate the application of the principles of the invention to a revolving door.

Such door construction comprises a pair of arcuate sealing panels or jams 75, which may be of tempered or untempered glass or other suitable material and which at their top and bottom edges are secured, for example by embedding, respectively, in ceiling 76 and floor 77. The outer faces of these panels are abutted by walls 78 which may also be of tempered or untempered glass, or other building material e. g., hollow glass blocks.

Door 79 mounted to revolve concentrically between panels 75, comprises a main panel 81 of tempered glass and a pair of panels 82 so hinged that they may at will be folded upon, or extended at right angles to panel 81.

The bottom of the door is supported by and rotates upon a mechanism, comprising a housing 83 of cast iron, bronze, or other material, embedded in the floor 77 of the building, concentrically with respect to panels 75. This housing comprises a bottom portion 86 bored and tapped as shown at 87, to receive a threaded vertically adjustable plug 88, having a gear 89 upon its upper extremity, revolving in an enlarged portion 91 of bore 87. Gear 89 and plug 88 are rotated by a splined pinion 92 journaled at its lower extremity in housing 83 and its upper extremity in a cover 93 fitting in a recess 94 about the top of portion 91 of bore 87.

The top of the pinion may be slotted or otherwise formed to receive a screw driven or other device for actuating the mechanism to rotate the plug.

Plug 88 is axially bored as indicated at 96 and rabbeted as indicated at 97 to receive upper and lower thrust bearings 98 and 99, respectively which provide bearings for shoulders 101, and 102 respectively of spindle 103.

The upper extremity of spindle 103 is shouldered as shown at 104 and fits into a recess 105 in a casting 106, which as shown in Fig. 6 is approximately cruciform in outline.

The main body 107 of the member 106 fits into notch 108 medianly located in the lower edge of panel 81 and is provided with upwardly-extending flanges 109 for gripping the sides of the latter. These flanges may be welded to, or formed integrally with the casting. The portion of the panel gripped by the casting and the flanges may be protected by means of a layer 111 of resilient material. Positive pressure by the

flanges upon the glass is assured by means of sleeve bolts 113 which extend through openings in the flanges.

If desired, semi-circular recesses 112 and 113a may be formed respectively in the glass and the member 107 to receive the bolts 113. However, in most cases they are not strictly essential.

A construction, in which the semi-circular recesses, e. g. recess 24, are omitted, is shown in Figs. 9 and 10. Aside from the omission of the recesses in the glass and the corresponding bolts, the structures are identical with those disclosed in Figs. 1, and 2. In order to distinguish the numerals of Figs. 9 and 10 from those of Figs. 1 and 2, prime marks have been applied. Aside from the latter indicia the numerals correspond to those of the first two figures.

Wings 114 are formed upon casting 106 and are bored as indicated at 116 to receive pintles 117, upon which are journaled castings 118, shown in Fig. 5. The latter castings are disposed in notches 119 formed in the lower inner corners of panels 82 and correspond to recesses 19 described in connection with Fig. 1. The casting and the adjacent portions of the glass are clamped by plates 121 corresponding to plates 16. Bolts 122 corresponding to bolts 21 may extend through the plates.

The panels are held in extended position by means of diagonal braces 123 (shown in Fig. 3), the extremities of which are connected by bolts 124 to lugs 126, upon plates 121 and flanges 109. It will be noted that the lugs upon plates 121 are slightly higher than those upon the flanges 109, to permit the lugs to swing into axial alignment when the panels are folded back. A bolt may then be dropped through the openings to maintain the panels in folded position.

Castings 118 and wings 114 of casting 106 are provided with semi-circular grooves 127 which, when the wing or folding panels 82 are extended, provide openings for bolts 128, shown in Fig. 5. These bolts function as keys which may be relied upon to hold the wings in position. The braces 123 may then be eliminated if desired.

In order to provide a pintle for the top of door 19, panel 81 is notched at its upper edge to receive a cruciform casting 131 corresponding closely in outline to the casting 106. The casting is provided with flanges 132 like flanges 109 through which extend clamping bolts 133. These bolts are received in notches in the edge of the panel 81 and thus securely lock the latter in place.

The wings 134 (shown in Fig. 5) upon casting 131 are bored to receive bearing pins 136, corresponding to pins 117, and fitting into openings in castings 137, that substantially correspond in design and mounting to castings 118.

Casting 131 at the median point thereof is bored at 138 to receive a downwardly-projecting pin 139, which pin extends upwardly through a plate 141 mounted in ceiling 16. The pin extends through a boss 143 upon the top of the plate. The boss is slotted as shown at 144 and the end of a lifting lever 146 operates in this slot and engages a recess 147 in the pin. The means for mounting and operating this lever corresponds to that described in connection with the lever 41 and need not be described in further detail.

Since it is necessary substantially to space the edges of the revolving panels 81 and 82 from the curved stationary panels or jams 15, in order to prevent pinching of the hands of users of the

door, some yielding, or flexible sealing strip must be provided upon the edges of the panels. Figs. 7, 8 and 9 illustrate various convenient forms of such strips.

5 In the form shown in Fig. 7, a channel-like member 150 of rubber, vinyl resin, thin spring metal, or other resilient material is clipped or cemented over the edge of the glass and is provided along its back with a flexible fin 151 designed to wipe the surface of the panels 15 as the door revolves.

15 It is again emphasized that indentations or notches formed in the door panel must be suitably rounded at the corners along lines of curvature having radii equal at least to half the thickness of the door panel. However, it is possible to obviate the necessity of recesses with rounded angles by clipping away a triangular portion at the corner by a single straight cut. Notches 24 may then be formed in the oblique edge. Holes or openings formed in the panel must have a diameter at least equal to the thickness of the door and must be spaced from the corners of the panels a distance at least equal to 6 times the thickness of the panels. If these rules are not observed spontaneous shattering of the panel is likely to occur.

ture being at least equal to the thickness of the slab, the blocks being secured in position by plates engaging and gripping opposite faces of the slab, and directly transmitting stresses upon the blocks to the glass of the slab the slab constituting the sole connection in the door between the pintle mountings.

3. A door for a building, which door comprises a closure element consisting of a single monolithic panel of glass tempered inherently to shatter into small rounded fragments upon rupture of the surface of the panel, and a plurality of hinges secured directly to the edges of the panel in spaced relation, the hinges each comprising an intermediate body portion engaging an end portion of the panel and extending across from face to face of the panel, said intermediate portion being formed with means providing a pivotal connection between the panel and a door frame, side plates gripping the sides of the panel and being directly secured to the intermediate body portion and holding the body portion from movement in a direction perpendicular to the

face of the panel and constituting means for the transmission of stresses exerted upon the body portion perpendicular to the face of the panel.

4. A construction as defined in claim 3 in which the side plates are united with the body portion to provide channel-like elements embracing the edge of the panel.

5. A door construction comprising a closure element consisting of a monolithic panel of glass adapted to fill a door opening in a building, said panel being so tempered that it will be shattered into small, harmless fragments upon rupture of the surface thereof, said panel further having a hinge secured directly to an edge thereof, which hinge comprises a channel-like member comprising an intermediate body portion having a pintle connection for the door and spanning from face to face of the panel and side plates secured as extensions to the said portion, and gripping the opposite faces of the panel to hold the hinge in position upon the panel.

ROBERT A. MILLER.
